US0D1046160S

(12) **United States Design Patent** (10) **Patent No.:** **US D1,046,160 S**
(45) **Date of Patent:** **** Oct. 8, 2024**

(54) **SURGICAL CONSOLE**

(71) Applicant: **Carl Zeiss Meditec AG**, Jena (DE)

(72) Inventors: **Walter Matuschek**, Aalen (DE);
Steffen Dambacher, Gauting (DE);
Dominik Hausen, Heidenheim (DE);
Christian Wolf, Aalen (DE)

(73) Assignee: **Carl Zeiss Meditec AG**, Jena (DE)

(**) Term: **15 Years**

(21) Appl. No.: **29/755,095**

(22) Filed: **Oct. 16, 2020**

(30) **Foreign Application Priority Data**

May 12, 2020 (EM) 007881859-0002

(51) **LOC (14) Cl.** **24-02**

(52) **U.S. Cl.** **D24/185**
USPC .....

(57) **CLAIM**

The ornamental design for a surgical console, as shown and described.

DESCRIPTION

FIG. 1 is a first perspective view of the surgical console of our new design;

FIG. 2 is a front elevation view of the surgical console of FIG. 1;

FIG. 3 is a right side elevation view of the surgical console of FIG. 1;

FIG. 4 is a left side elevation view of the surgical console of FIG. 1;

FIG. 5 is a top plan view of the surgical console of FIG. 1;

FIG. 6 is a rear elevation view of the surgical console of FIG. 1;

FIG. 7 is a bottom plan view of the surgical console of FIG. 1; and,

FIG. 8 is a second perspective view of the surgical console of FIG. 1.

The broken lines depict portions of the surgical console that form no part of the claimed design.

1 Claim, 8 Drawing Sheets
